DESIGN FOR A PENDANT

Frank Pina Miro, Brooklyn, N. Y.

Application July 5, 1940, Serial No. 93,444

Term of patent 14 years

To all whom it may concern:

Be it known that I, Frank Pina Miro, a citizen of the United States of America, and residing in Brooklyn, Kings County, State of New York, have invented a new, original, and ornamental Design for a Pendant, of which the following is a specification, reference being had to the accompanying drawing forming part thereof.

I claim:

The ornamental design for a pendant, as shown.

FRANK PINA MIRO.
